PROPELLER

Walter W. Everts, Baltimore, Md., assignor to
Everel Propeller Corporation, Baltimore, Md.,
a corporation of Maryland

Application July 3, 1940, Serial No. 343,889

6 Claims. (Cl. 170—164)

This invention relates to propellers and devices of similar character, and more particularly has reference to an automatic variable pitch propeller.

In general, automatic variable pitch propellers operate upon the theory of so constructing the propeller that the blade is capable of movement to alter the pitch as a result of some or all of the forces acting upon the blade when rotating. The present invention is directed to a propeller in which the blade is pivoted to the hub in such a way that it is capable of limited rotation and, in such movement, describes an arc of a cone.

An object of this invention is to provide a novel hub construction which is adapted for use in a propeller of the type above mentioned.

Yet another object of this invention is to provide means for mounting the propeller blade on such a hub.

A still further object of this invention is to provide a novel pivoting arrangement in such construction.

To accomplish the above and other important objects my invention in general embraces the concept of mounting a propeller blade upon a hub to permit limited rotation of the former to describe the arc of a surface of a cone. The principal forces in effecting such movement within the arc, during operation of the propeller, are centrifugal forces acting on the blade and the drag of the blade. Auxiliary means such as counter weights may be employed to effect equilibrium between these forces, and any other forces, encountered during rotation of a propeller. More specifically, the blade is pivoted upon the hub in such a manner as to insure the arcu-conical path desired for the particular propeller. While the position of the pivotal axis may be varied within certain limits to meet the exigencies of any particular situation, in general the pivotal axis is angularly disposed with respect to the plane of rotation of the propeller, and preferably lies in a plane which is perpendicular to such plane and also intersects the axis of rotation. A specific embodiment of my invention, showing certain detailed constructional advantages, is disclosed in the accompanying drawings and described hereafter, it being understood however that various departures may be made therefrom without exceeding the scope of my invention.

In the accompanying drawings, in which similar numerals refer to the same part:

Figure 1 is a front view of a propeller con-

structed in accordance with my invention, the propeller being in inoperative position.

Figure 2 is a view similar to Figure 1, but indicating the relative movement between the blade and hub which is possible during rotation of the propeller.

Figure 3 is a side view of the propeller, in which the solid and dotted lines of the blade represent two different positions that the blade

10 may assume during flight.

Figure 4 is a sectional view along the line 4—4 of Figure 2 looking in the direction of the arrows, and showing in detail by the dotted line the variation in pitch of the propeller resulting from movement of the propeller along the arc of the cone as above mentioned.

Figure 5 is a detailed view along the line 5—5 of Figure 1 looking in the direction of the arrows.

Figure 6 is a view along the line 6—6 of Figure 5 looking in the direction of the arrows.

Figure 7 is a view taken along the line 7—7 of Figure 5, but showing the sides of the hub open and the blade in a radial position and at its point of maximum pitch.

Figure 8 is a view generally similar to Figure 7, but showing the blades at their points of minimum pitch.

Figure 9 is a view along the line 9—9 of Figure 7 looking in the direction of the arrows.

Figure 10 is a view along the line 10—10 of Figure 8 looking in the direction of the arrows.

It will be observed that the assembled propeller comprises a hub generally designated 1 and blades designated generally 2 carried by the hub. The hub is adapted to be splined, or rigidly mounted in some other suitable manner upon a drive shaft 3.

Referring more particularly to Figure 5, the hub consists of a sleeve 4 which receives the drive shaft 3, and this sleeve is provided with a pair of radially disposed arms 5 and 6 which form in effect a recess for each blade, or more specifically for a blade socket. It will be noted that the arm 6 is of greater length than the arm 5, which is for the purpose of permitting the drilling of diagonally aligned apertures 7 and 8, respectively, through the two arms.

Extending the full length of the hub are side members 9 which are similar in construction. The side members are provided with ears 11 at each end which bend over the top and bottom of the hub and are pivoted upon the arm 6 at the front of the hub. The forward end of each side member 9 is provided with an inturned lip

12 which, upon opening the side members as shown in Figure 2, abuts against a cap 13 which closes the front of the sleeve 4.

The rear of each side member 9 is provided with an outwardly extending flange 14 which carries one or more pins 15, oppositely disposed with respect to corresponding pins on the other side member. The side members are apertured as at 16, as best shown in Figure 7, and a spring 17 passes through each aperture and is secured to the oppositely disposed pins 15. The springs resiliently urge the side members to a closed position to lie against a socket for the blade as will be later described, but upon rotation of the propeller the side members 9 are forced open due to centrifugal force to a position where the lips 12 abut against the cap 13.

The blades 2 are provided with the usual shanks which are held in a socket 18 by means of a pin 19. The socket 18 is drilled for a hole 21 which, when the socket is in assembled position in the hub, is aligned with holes 7 and 8 in the arms 5 and 6.

A pin is adapted to pass through the holes 8, 21 and 7 to form a pivot with which the socket 18 may swing to a predetermined degree, and, while any conventional type of pivot pin may be employed, I find that, if a counter-balance weight is necessary for opposing the centrifugal action on the propeller blades, the arm of such weight may be bent to serve as the pin. As shown in the drawings, a counterweight 22 is mounted upon an arm 23. This arm is bent to serve as the pivot pin 23a. A set screw 24 may be screwed into a threaded hole in the socket 18 to engage the pin 23a and hold it fixed both longitudinally and rotatively with respect to the socket 18.

It will be appreciated that the socket 18 in pivoting with the pin 23a incurs a twisting movement with respect to the arms 5 and 6, as best shown in Figure 8. This is possible in view of the fact that the diagonally opposed corners of the socket 18 are beveled as at 25 and 26 (see Figure 9), which permits of limited twisting movement, and the extent of this bevel of course determines the amount of twisting movement possible. It will be appreciated that in such pivoting and twisting of the socket 18, the blade 2 moves between the positions indicated by the solid and dotted lines of Figures 2-4, with a consequent change in the pitch of the blade.

In actual operation, the blade has a maximum pitch when the blade is radial with respect to the axis of rotation, as shown in Figure 1, and by the solid lines in Figures 2, 3 and 4. The blade is in this position when the hub is stationary inasmuch as the side members 9 maintain it in this position as shown in Figure 6. Upon rotation of the propeller, the side members open to a position shown in Figures 2, 7 and 8, and the blade is then free to assume the optimum pitch for the operating condition encountered, within the limits determined by the bevels 25 and 26 of the socket 18. The propeller is designed so that the blades will be in a condition of substantial equilibrium for any given operation. In other words, the angle at which the socket 18 is disposed with respect to the arms 5 and 6, the use (number, weight and disposition) of the counterweights, and the degree of bevels 25, will all be designed upon the determination of various factors involved in the particular airplane under consideration, all in accordance with recognized aeronautics practice. In general, the 75

specific position of the blade with respect to the hub for any given condition of flight, will be principally the function of centrifugal force upon the drag of the blade during rotation (although other factors may be encountered to a less degree). As indicated above, suitable counterweights may be used to modify these forces.

In actual operation the drag upon the propeller is determined by the engine torque characteristics. The tendency of the propeller drag is to urge the blade out of a radial position and hence into a lower pitch. This tendency is opposed by the centrifugal forces acting upon the blade tending to urge the blade into higher pitch. The centrifugal force effects are a function of the propeller revolution speed and of the angular position of the blade with respect to the hub. The blade will thus find an equilibrium position or pitch dependent upon the engine torque, propeller speed, and the design of the blade for the particular propeller.

It will be seen from the foregoing that I have provided a propeller in which the blades are adapted to automatically assume positions of varying degrees of pitch, and which, for any given condition of flight, is in a position of substantial equilibrium. It will be appreciated that the mechanical structure of this propeller is economical and efficient and provides novel means for securing the automatic variations in pitch.

While I have described the invention with particular respect to a two-blade propeller for an airplane, the precise number of blades is immaterial, and furthermore, my inventive concept may be applied to other devices than airplane propellers. Consequently, the use of the expression "propeller" in the claims is not to be strictly construed, but is designed to include all devices of this general character, such as fans, etc.

I claim:

1. A propeller assembly adapted to be mounted on a drive shaft of an airplane comprising a sleeve adapted to be secured to the drive shaft, spaced arms extending radially from the sleeve, a propeller blade pivotally mounted between the said arms, a counterweight for said assembly, a section of said counterweight extending through the said arms and forming the pivot upon which the blade is mounted, said section lying in a plane perpendicular to the plane of rotation of the propeller, and the axis of said section intersecting the axis of rotation at an angle of less than 90°.

2. A propeller assembly adapted to be mounted on a drive shaft of an airplane comprising a sleeve adapted to be secured to the drive shaft, spaced arms extending radially from the sleeve, a pair of propeller blades the roots of which are mounted between said arms in opposed relation, side members hinged on opposite sides of one of said radial arms, each of said side members being designed to engage one of the aligned sides of the said propeller roots, resilient spring means to hold the said side members against the propeller blade roots until separated by centrifugal forces caused by the revolution of the propeller, a pair of pivot pins extending through the said arms, each pin forming a pivot upon which one of the roots of the said propeller blades is mounted, said pins lying in a plane perpendicular to the plane of rotation of the propeller, and the axis of each pin forming with the axis of rotation an angle of less than 90°.

3. A propeller assembly comprising a sleeve

for mounting on a drive shaft of an airplane engine, arms extending radially from the sleeve and fixed relatively thereto, said arms being spaced axially of the sleeve, a propeller blade having its shank mounted between said arms, a pivot pin extending through said arms and the shank of the propeller blade and forming a pivot upon which the propeller blade is mounted for pivotal movement, said pivot pin lying in a plane containing the axis of said sleeve and the axis of said pin forming an angle of less than 90° with the axis of said sleeve, plate means positioned on opposite sides of the blade shank, and resilient means urging said plates into engagement with the shank to urge said blade to a predetermined position.

4. A propeller assembly comprising a sleeve for mounting on a drive shaft of an airplane engine, arms extending radially from the sleeve and fixed relatively thereto, said arms being spaced axially of the sleeve, a propeller blade having its shank mounted between said arms, a pivot pin extending through said arms and the shank of the propeller blade and forming a pivot upon which the propeller blade is mounted for pivotal movement, said pivot pin lying in a plane containing the axis of said sleeve, the axis of said pin forming an angle of less than 90° with the axis of said sleeve, said pivot pin being rotatably mounted in said arms and fixed to the shank of the propeller blade, a crank arm extending from one end of said pivot pin and a weight responsive to centrifugal action mounted on the free end of said arm.

5. A propeller assembly comprising a sleeve for mounting on a drive shaft of an airplane

engine, arms extending radially from the sleeve and fixed relatively thereto, said arms being spaced axially of the sleeve, a propeller blade having its shank mounted between said arms, a pivot pin extending through said arms and the shank of the propeller blade and forming a pivot upon which the propeller blade is mounted for pivotal movement, said pivot pin lying in a plane containing the axis of said sleeve, the axis of said pin forming an angle of less than 90° with the axis of said sleeve, flap means hingedly mounted on one of said arms, and resilient means urging said flap means into engagement with the shank of the propeller blade to maintain said blade in a predetermined position.

6. A propeller assembly comprising a sleeve for mounting on a drive shaft of an airplane engine, arms extending radially from the sleeve and fixed relatively thereto, said arms being spaced axially of the sleeve, a propeller blade having its shank mounted between said arms, a pivot pin extending through said arms and the shank of the propeller blade and forming a pivot upon which the propeller blade is mounted for pivotal movement, said pivot pin lying in a plane containing the axis of said sleeve, the axis of said pin forming an angle of less than 90° with the axis of said sleeve, flap means hingedly mounted on one of said arms, resilient means urging said flap means into engagement with the shank of the propeller blade to maintain said blade in a predetermined position, and weights on said flap means operable by centrifugal action during rotation of the propeller to oppose the action of said resilient means.

WALTER W. EVERETT.
